ANDREW J. BARNHART AND CLITHEROW N. TRIMMELL, OF PLACENTIA, CALIFORNIA.

BLEEDING DEVICE AND TUBING JAR.

Application filed July 18, 1923. Serial No. 652,328.

To all whom it may concern:

Be it known that we, ANDREW J. BARNHART and CLITHEROW N. TRIMMELL, citizens of the United States, residing at Placentia, in the county of Orange and State of California, have invented new and useful Improvements in Bleeding Devices and Tubing Jars, of which the following is a specification.

10 Our invention relates to jarring device or well drilling tubing, and a purpose of our invention is the provision of a device of extremely simple, durable, and efficient construction by which a drill stem or tubing can, through a manipulation of the tubing from the top of the well, be converted into relatively movable units to allow reciprocation of the upper unit in effecting a hammering or jarring of the lower or drilling 20 carrying unit whereby the freeing of the drill tube can be effected.

It is also a purpose of our invention to provide a jarring device which includes means by which the bleeding of the upper 25 drill tubing unit can be automatically effected upon movement of the jarring device to active position, thus draining the tubing, and thereby permitting the more ready reciprocation of the tubing.

30 Although we have herein shown and will describe only one form of jarring device embodying our invention, it is to be understood that various changes and modifications may be made herein without departing 35 from the spirit of the invention and the spirit and scope of the appended claims.

In the accompanying drawings Fig. 1 is a view showing in vertical section one form 40 of jarring device in applied position with respect to two adjacent sections of a drill tube.

Fig. 2 is a view showing the jarring device in side elevation and in applied position to the drill tubing, but in active position to permit reciprocation of the upper section of the drill tubing.

Referring specifically to the drawings in which similar reference characters refer to similar parts, our invention in its present 50 embodiment comprises a hammer element H, and an anvil element A, the former being rigidly connected to the upper section 15 of any two adjacent sections of a drill tubing by means of a connecting sleeve 16 having 55 threaded engagement with the tube section 15 and with the upper ends of the hammer

element so that the confronting ends of the tube are securely held in abutting relation. The anvil element is rigidly connected to the lower tube section 17 through the 60 threaded connection 18, and the anvil element is made of an upper section 19 and a lower section 20 detachably connected by means of an over-lap joint 21.

The elements A and H are both of tubular form and the internal diameter of the former is sufficient to allow of free reciprocating movement thereof upon the hammer element. Normally, the anvil element is secured against movement with respect to the 65 hammer element by a reduced upper end 21^a connected to the hammer element by a left-hand screw-threaded connection 22. The uppermost position of the element A upon the element H is defined by the sleeve 16, it 70 being noted that the reduced end 21^a abuts the lower end of the sleeve 16. The lowermost position of the sleeve 16 is defined by an annular shoulder 23 formed on the hammer element at the upper end of the 75 threaded connection 22.

The hammer-element H is provided at its lower end with a head 24 which exceeds in diameter that of the element and which constitutes the hammer of the jarring device. 80 This head 24 is adapted to strike against a head 25 formed interiorly of the element A and which constitutes the anvil of the jarring device, it being understood that the head 25 is also of annular form to correspond to the head 24. It will be particularly noted that the lower end of the anvil 85 element is reduced in internal diameter to provide a seat or shoulder 26 which constitutes an abutment for the hammer head 24 90 when the latter is in its lowermost position.

For the purpose of allowing the bleeding or discharge of liquid from the jarring device and that portion of the well tubing above the device, the hammer element H is 100 formed with perforations 27 which are exposed when the anvil element is disengaged, as clearly shown in Fig. 2.

In practice the anvil element A is normally held against movement by virtue of its threaded connection 22 with the hammer element H so that the jarring device serves to provide a rigid connection between the sections 15 and 17 of drill tubing. The drill tubing may now be reciprocated in the usual manner to effect operation for the drill tool within the well. Should the drill tool for 110

any reason become locked against movement within the well, a freeing of the tool can be effected by rotating the section 15 in a clock-wise direction so as to unscrew the threaded connection 22 and thereby effect a release of the anvil element A. It will be understood that all of the other threaded connections are right-hand screw threads so that rotation of the tubing will be ineffective 10 to disconnect the threaded connections during the disconnection of the connection 22. With the anvil elements A released, it will gravitate from the position shown in Fig. 1 to that shown in Fig. 2 wherein the anvil 15 head 25 reposes upon the hammer head 24. The upper tube section 15 is now free to be reciprocated to impart a corresponding movement to the hammer head 24 so that a vertical jarring of the anvil element A and the tube section 17 connected therewith is 20 now effected. This movement effects a vertical jarring of the anvil element A and the tube section 17 connected therewith with the result that a loosening of the tool within 25 the well is effected.

It will be noted that when the anvil element A is released, any liquid contained within the device and the tube sections above the device is free to pass out of the perforations 27 thus relieving the tubing and device of the weight of the liquid and thereby facilitating the reciprocating of the tube.

What we claim is:

1. A lower drill tube section, an anvil element screwed upon the drill tube section and having an enlarged cylindrical bore with an annular shoulder at the upper end of the bore and forming a head and having a screw thread above the shoulder, a

hammer element extending through the 40 screw thread past the shoulder into the bore and having a head upon its lower end adapted to strike the shoulder and adapted to reciprocate in the bore, there being a screw 45 thread upon the hammer element to fit the screw thread of the anvil element and hold the parts rigid, a coupling sleeve screwed upon the upper end of the hammer element, and an upper section screwed into the coupling sleeve so that the parts form a rigid 50 portion of a drill tubing, and so that when the lower part is held and the upper part rotated the hammer element will be screwed out of the anvil element to serve as a jar.

2. In drill tubes, a combined tube connector and anvil and hammer forming a drill jar comprising a connecting non-perforated tubular sleeve threaded on a lower tube section, said sleeve having a lower section and an upper section joined by a lap screw joint, said upper section having an annular anvil face on its inner upper end, a tubular hammer having an annular hammer member at its lower end and secured at its upper end to an upper drill tube by a threaded sleeve connection, and reverse threads on said hammer member adjacent its upper end engaging with threads on the upper end of said anvil connector member whereby, by an unscrewing 70 action, the upper and lower drill tubes are separated and by a reciprocating movement of the upper tube a jarring action is obtained.

In testimony whereof we have signed our 75 names to this specification.

CLITHEROW N. TRIMMELL.
ANDREW J. BARNHART.
